GUIDE MEANS FOR FLUSH TANK VALVES

Joe A. Deatherage, Seagraves, Tex.

Application July 23, 1951, Serial No. 238,149

1 Claim. (Cl. 4-57)

1

My invention relates to improvements in guide means for flush tank valves, and the like.

The primary object of my invention is to provide efficient guide means for the ball float valve and valve stem of such tanks especially designed to attain precision seating of the valve without retarding operation of the same.

Another object is to provide guide means of the character and for the purpose above set forth which is attachable readily and quickly to the usual overflow stand pipe of such tanks, and which is inexpensive to manufacture, install and service.

Other and subordinate objects, within the purview of my invention, together with the precise nature of my improvement will be readily understood when the succeeding description and claim are read with reference to the drawings, accompanying and forming part of this specification.

In said drawings:

Figure 1 is a fragmentary view in vertical section, partly in side elevation, illustrating my improved guide means installed in a flush tank;

Figure 2 is a similar view with the guide means turned through an angle of 90 degrees;

Figure 3 is a fragmentary view in plan;

Figure 4 is an enlarged view in horizontal section taken on the line 4-4 of Figure 2;

Figure 5 is a similar view taken on the line 5-5 of Figure 2;

Figure 6 is a view in vertical section taken on the line 6-6 of Figure 4; and

Figure 7 is a fragmentary view in vertical section taken on the line 7-7 of Figure 6.

Referring to the drawings by numerals, according to my invention, guide means, designated generally 1, for the usual type of vertically movable ball, float valve 2, and the upstanding stem, or rod 3 thereof are provided in a flush tank 4, said means comprising a valve guide cage 5 of skeleton form, having a stem guide 6 rising therefrom. The valve cage 5 is of vertically elongated cylindrical form with vertical water inlet slots 7 therein, an upwardly tapering top 8, and an annular bottom 9 resting on the usual valve seat 10 of the flush tank 4 to guide the ball valve 2 in its movement onto and off said seat 10. The valve cage 5, at its bottom, is flared, as at 11, to obviate binding of the valve 2 therein at the valve seat 10 because of possible manufacturing variations in the size of the valve 2, or other imperfections in said valve. A bottom notch 12 is provided in the bottom 9 to straddle the usual horizontal branch inlet duct 13 of the usual overflow standpipe 14 of the flush tank 4 if, as fre-

2

quently occurs, the branch duct 13 is offset above the valve seat 10 to which it leads.

The stem guide 6 is tubular, rises from the top 8 of the cage 5 axially of said cage and slidably receives the usual upper end hook 15 on the stem 3. Longitudinal slots 16 are provided in the stem guide 6, preferably in 90 degree angular relation. The lower lateral end 17 of the usual valve lift rod 18, with the usual eye 19 on said end encircling the stem 3 below the hook 15 is extended out of one of the slots 16 selected in accordance with the desired position of said lift rod 18 circumferentially of said stem guide 6. The upper ends of the slots 16 terminate from the top 8 a distance less than the height of the cage 5 for coaction with the lower end 17 of the lift rod 18 to limit upward movement of said rod 18, stem 3 and valve 2 and thereby prevent the valve 2 from being lifted so as to be bumped against the top 8 of the cage 5 and the connection between the valve 2 and stem 3 loosened, the connection between such valves and stems being a threaded connection, as illustrated at 20, which may become loosened by impact of the valve against a fixed part during upward movement of said valve. Preferably, the upper ends of the slots 16 are so arranged that the valve 2 can only be lifted sufficiently to start the same floating.

A C-clamp 21 is provided for attaching the guide cage 5 to the overflow standpipe 14 of the flush tank 4. The C-clamp 21 comprises a fixed jaw section 23 extending horizontally from the top 8 at one side of said cage 5, and a complementary removable jaw section 24 attachable to the section 23 by a pair of upper and lower screws 25, 26. The complementary removable jaw section 24 is formed with a spacing rib 27 for spacing said section from the fixed section 23 to prevent said sections from freezing together from rust, or the like.

As will be obvious, the valve 2 is guided by the guide cage 5 in its vertical movement onto and off the seat 10, while the upper end, or hook 15, of the stem 3 is guided by the stem guide 6. The requisite amount of clearance is provided between the guide cage 5 and valve 2 and between the hook 15 and stem guide 6 to obviate frictional resistance to vertical movement of said valve 2 and hook 15.

The foregoing will, it is believed, suffice to impart a clear understanding of my invention, without further explanation.

Manifestly, the invention, as described, is susceptible of modification without departing from the inventive concept, and right is herein

reserved to such modifications as fall within the scope of the appended claim.

Having described the invention, what is claimed as new is:

In a flush tank having a bottom valve seat, an overflow stand pipe branched to said seat, a ball valve on the lower end of a stem and vertically movable onto and off said seat, and a lift rod for the stem having a lateral end operatively connected to the upper end of the stem, a cylindrical skeleton cage for guiding said valve provided with a top and an annular internally flared bottom resting concentrically on said seat to guide the valve to the seat and being notched to fit over said branch, a tubular stem guide rising 15 from said top and provided with a longitudinal slot therein through which said lateral end of the lift rod extends into said guide for vertical movement in operative connection with said stem, and means attaching said cage to said pipe, the 20

upper end of the slot terminating from said top a distance less than the height of the cage for coaction with said lateral end of the lift rod to limit upward movement of said rod, stem and valve and to prevent the valve from being lifted against said top.
